UNITED STATES PATENT OFFICE

2,050,744

CORN HUSKING DEVICE

Clark E. Williams, Stuart, Iowa

Application June 12, 1933, Serial No. 675,433

1 Claim. (Cl. 130—4)

The principal object of this invention is to provide a corn husking tool that greatly increases the amount of corn that can be manually husked in one day by an individual.

5 A still further object of this invention is to provide a corn husking device that saves the hands of the user and requires a minimum amount of energy for its use in the removal of the ears of corn from the stalk and husk.

10 A still further object of my invention is to provide a corn husking tool that is light in weight, thereby making corn husking less tiresome.

15 A still further object of this invention is to provide a corn husking device that is economical to manufacture and durable in use.

These and other objects will be apparent to those skilled in the art.

20 My invention consists in the construction, arrangement and combination of the various parts of the device, whereby the objects contemplated are attained as hereinafter more fully set forth, pointed out in my claim and illustrated in the accompanying drawing, in which:

25 Fig. 1 is a front view of one form of my corn husking tool ready for use.

Fig. 2 is a side-sectional view of a portion of one of the metal parts showing the outwardly extending corn husk engaging lugs.

30 Fig. 3 is a cross-sectional view of the portions of two of the metal parts, illustrating the metal link for holding the two metal parts to each other.

Fig. 4 is a front view of a different form of construction of my corn husking tool.

Fig. 5 is an inner side view of the thumb portion of the device shown in Fig. 4.

Fig. 6 is a cross-sectional view of the construction shown in Fig. 1 and is taken on line 6—6 of that figure.

Referring to the construction shown in Fig. 1 I have used the numeral 10 to designate a piece of flexible material such as leather and designed to cover the lower area of the palm of the user.

45 The numeral 11 designates the usual wrist band secured to the rear end of the part 10. The numeral 12 designates a flat metal bar secured by suitable means to the forward end of the member 10 and having its two outer end portions curved to extend around the top side and bottom side respectively of the palm of the hand of the user. By so curving the end portions of this member 12 the same will be prevented from undue transverse movement relative to the hand

55 of the user. The numeral 13 designates a flex-

ible strap secured at one end to one end of the member 12. The numeral 14 designates a flexible strap secured at one end to the other end of the member 12. These two straps 13 and 14 are adjustably secured together by a buckle or like 15. The numeral 16 designates a plurality of husk engaging lugs on the member 12. These lugs 16 as shown in the drawing are formed by cutting into each edge of the member 12 and bending the cut portions outwardly, as shown 10 in Fig. 2. If the cut portions are diametrically opposite from each other on the member 12 they should extend in opposite directions in order that when the lugs 16 are bent outwardly they will be staggered relative to each other, as 15 shown in Fig. 1.

The lugs 16 are blunt and are not sharpened, as shown in Fig. 2. The numeral 17 designates two spaced apart longitudinally extending slots formed in the member 12 near its forward outer 20 edge, as shown in Fig. 1. The numeral 18 designates a straight flat metal bar member similar to the member 12, but having a length much less than the length of the member 12 and not having its two end portions curved. This member 18 has formed near each of its side edges lugs 19 which are duplicates of the lugs formed on the member 12. The numeral 20 designates two spaced apart longitudinally extending slots in the member 18 near its rear edge. These two 30 slots 20 are similar to the slots 17 and are spaced apart the same distance that the slots 17 are spaced apart. The members 12 and 18 are connected to each other by two flat links 21 engaging and extending between the slots 20 and the slots 17 respectively, as shown in Fig. 1 and Fig. 3. The numeral 22 designates two spaced apart longitudinally extending slots in the member 18 near its forward marginal edge. The numeral 23 designates a straight flat metal bar 40 member which is approximately an exact duplicate of the member 18. The numeral 24 designates the usual lugs formed on the member 23. The numeral 25 designates two spaced apart longitudinally extending slots in the member 23 near its rear marginal edge. These slots 25 are similar to the slots 22 and are spaced apart the same distance as the distance between the two slots 22. The numeral 26 designates two flat metal links connecting the member 23 with the member 18 by engaging and extending between the slots 25 and the slots 22 respectively. Straps 27 are secured by suitable means to each end of the member 18 and the member 23 for se- 50 55

curing the same to the fingers of the user of the device. The numeral 28 designates a flat metallic bar member having a comparatively short length and being slightly curved to fit the inside curvature of the thumb of the user. This member 28 has the usual lugs 29.

The numeral 30 designates two spaced apart longitudinally extending slots in the member 12 near its upper rear marginal edge. These slots are spaced apart much closer than are the previously explained slots. The numeral 31 designates two spaced apart longitudinally extending slots in the member 28 near its inner marginal edge, as shown in Fig. 1. The numeral 32 designates two flat metal links engaging and extending between the slots 30 and 31 respectively, as shown in Fig. 1, for connecting the member 28 with the member 30. These two flat links 32 are bent and the link closest to the palm of the hand is longer than the other in order to conform with the angle of the thumb of the user and permit the member 28 to assume a normal position across the face of the thumb. The numeral 33 designates two spaced apart longitudinally extending slots in the member 28 near its outer marginal edge. The numeral 34 designates a flat metallic bar member similar to the member 28 and slightly curved to fit the thumb of the user. This member 34 has the usual lugs 35. The numeral 36 designates two spaced apart longitudinally extending slots in the member 34 near its inner marginal edge. The numeral 37 designates two flat metallic links connecting the member 34 with the member 28 by engaging and extending between the slots 36 and 33 respectively. The numeral 38 designates straps for securing the members 28 and 34 to the thumb of the user.

In the construction shown in Fig. 4 the metallic members 12, 18, 23, 28, and 34 are substantial duplicates of the same members shown in the construction in Fig. 1 and like numerals are used to designate the similar elements. In the construction shown in Fig. 4 and Fig. 5 the metal links 21, 26, 32, and 37 are dispensed with and the members 12, 18, 23, 28, and 34 are secured together and properly spaced apart from each other by being secured by suitable means to a mitten of flexible material such as leather and which I have designated by the numeral 39.

The use of the flat metal links and slots in which the links are hingedly attached, as shown in Fig. 3, is highly desirable in the construction shown in Fig. 1 as they permit the normal closing and opening of the hand of the user, but prevent any substantial longitudinal move-

ment of the members 12, 18, 23, 28, and 34 relative to each other.

In the use of the device I recommend that it be used on the left hand. To husk an ear of corn the ear is grasped by the left hand which will cause the lugs to successfully engage the husk, but due to their blunt nature will not pierce through and seriously engage the ear of corn itself. With the ear of corn thus held by the left hand the right hand pushes the top of the ear of corn to one side, thereby breaking the same from the stalk and slipping it out of the husk. The action is a natural and easy one and an ear of corn can be husked much more rapidly than with previous known devices of this art.

When the construction shown in Fig. 4 is used the mitten is placed on the left hand in the usual manner. When the construction shown in Fig. 1 is used the band 11 is fastened around the wrist and the members 28 and 34 fastened to the thumb by the straps 38. The member 12 is fastened around the top and bottom sides and across the palm of the hand of the user. The bar 18 is fastened to the hand and should rest across the rear end portions of the fingers. The bar 23 should be fastened to the hand in such a manner that it will rest on the forward end portions of the fingers. The construction shown in Fig. 1 may be used with or without a glove.

Some changes may be made in the construction and arrangement of my improved corn husking device without departing from the real spirit and purpose of my invention, and it is my intention to cover by my claim any modified forms of structure or use of mechanical equivalents which may be reasonably included within their scope.

I claim:

In a corn husking tool, a member designed to be worn on the hand of the user, a plurality of parallel substantially flat metallic members secured on said member designed to be worn on the hand of the user, and a plurality of lugs on the two marginal side edges of each of said metallic members extending away from said flat members at right angles thereto and with their longitudinal widths extending transversely of the longitudinal axes of said flat members; said lugs each being formed from the said flat member of which it is a part by cutting said flat member first inwardly from its marginal edge and then longitudinally of its axis and then by bending the cut portion upwardly from said flat member into a lug.

CLARK E. WILLIAMS.
